(57) **CLAIM**

What is claimed is the ornamental design for a smartwatch, as shown and described.

DESCRIPTION

FIG. 1 is a front, right and top side perspective view of a smartwatch showing our new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof.

FIG. 9 is an enlarged partial view of FIG. 1; and,

FIG. 10 is an enlarged partial view of FIG. 2.

The broken lines shown in the drawings represent portions of the smartwatch that form no part of the claimed design.

1 Claim, 10 Drawing Sheets
